CLAIM

The ornamental design for a medical instruction plate for an insufflation apparatus, as shown and described.

DESCRIPTION

FIG. 1 is a front elevational view of a medical instruction plate for an insufflation apparatus, showing my new design, the bottom view being identical thereto;

FIG. 2 is a top plan view thereof;

FIG. 3 is a rear elevational view thereof; and

FIG. 4 is a side elevational view thereof, the opposite side being identical thereto.
